UNITED STATES PATENT OFFICE.

ALBERT E. C. CLOTHIER, OF SWARTHMORE, PENNSYLVANIA.

REVERSIBLE CUFF.

1,312,100

Specification of Letters Patent. Patented Aug. 5, 1919.

Application filed July 22, 1915. Serial No. 41,236.

To all whom it may concern:

Be it known that I, ALBERT E. C. CLOTHIER, a citizen of the United States, and resident of Swarthmore, in the county of 5 Delaware and State of Pennsylvania, have invented certain new and useful Improvements in Reversible Cuffs, of which the following is a specification.

My invention relates to improvements in 10 reversible cuffs and the object of my invention is to furnish a detachable cuff of soft material that can when soiled be conveniently reversed so as to expose a perfectly clean part.

15 My invention is illustrated in the accompanying drawings which form part of this specification, in which similar numerals of reference indicate similar parts throughout the several views, and in which:—

20 Figure 1, is a side elevation of the lower end of a shirt sleeve to which my improved cuff is attached:

Fig. 2, a view showing the lower end of the sleeve opened and flattened out, the cuff 25 being removed:

Fig. 3, a view of cuff detached from sleeve and opened to show hole for tab in band:

Fig. 4, a view showing the lower part of sleeve and cuff, the latter being reversed, or 30 turned inside out, the double portion of cuff being slightly opened to show tab passing through wristband:

Fig. 5, a view similar to that shown in Fig. 4, the cuff being fully attached to sleeve 35 and folded back ready to receive cuff button when the two ends are brought together:

Fig. 6, a view similar to that shown in Fig. 1, the cuff being reversed:

Fig. 7, a cross section of Fig. 5 on line 40 7—7:

Fig. 8, a cross section of Fig. 1 on line 8—8.

For convenience in reading the drawings, I have indicated one side of the cuff with a 45 light ground and dark stripes, and the other side with dark ground and light stripes.

10 designates a shirt sleeve and 11 my improved cuff. 12—12, 13—13, 14—14 are 50 registering button holes at the sides of the cuff, and band 15 in which are situated the holes 13, which register with the above holes in the cuff 11, a band at one end of the cuff extending from one side of the cuff to the other. 16 is a button hole or slit in band 55 15. 17 is a tab sewed at the middle of that end of the cuff which carries band 15. 18 a

slot in the cuff at base of tab 17 through which the tab, which is employed to secure the cuff to the wristband, can be passed when the cuff is reversed.

In applying the cuff to the wristband the latter is flattened out as shown in Fig. 2 and the wristband 20 is placed between the cuff proper and the band 15, the tab 17 being drawn first through the central hole 19 in 60 the wristband 20 and then through the hole 16 in the cuff band 15. The outer part 22 of the cuff is now folded back so as to cover the cuff band 15 in which position the holes 12 in the outer part 22 of the cuff are in register with the holes 13 in the cuff band, with the holes 14 in the inner part of the cuff, and, with the holes 21 formed in the wristband of the sleeve. A cuff button may now be passed through these sets of holes, first to 65 one side of the cuff and wristband, and then through the other, in order to secure opposite sides of the cuff in the usual manner.

If the cuff becomes soiled it is removed from the sleeve and is turned inside out, that is to say it is turned so that the side of the band 15 originally facing outward is now facing inward, and the tab 17 is drawn through the slot 18 so that it again faces the band 15. The wristband is now placed between the cuff band 15 and the cuff, the tab is drawn through the hole 19 in the wristband and the hole 16 in the cuff band, and the cuff is folded over the cuff band when the cuff buttons or links are passed through 70 the holes 13—14—21 as before described.

Referring to Figs. 3 and 4, it will be observed that the ends of the cuff adjacent to the ends of the cuff band 15 are undercut as indicated at 23. The purpose of this is to make this end of the cuff a trifle shorter than the other, or outside, end so that when the latter is folded over finally it will completely cover this cut under part in order to make 75 a slight finish.

It will be evident that the cuff comprises an outer member and an inner member, whichever way it be turned, whether with the surface shown in Fig. 3 be turned so that the two parts face each other, or with the opposite face so turned; that the band 15 with the inner cuff portion forms a complete circumferential band, which is turned inside out in the same sense that a stocking is so turned, when the cuff is reversed. The 80 tab 17 is capable of passage through the slot 18 to provide for its reversal.

Having thus described my invention I claim as new and desire to secure by Letters Patent:—

1. As an article of manufacture, a detachable cuff for shirt sleeves comprising a cuff portion foldable to present different surfaces outwardly, in combination with a connecting band joining those ends of the cuff which extend parallel to the length of the wearer's arm and adapted to be turned inside out to present different surfaces toward the cuff, extending circumferentially of the wrist of the wearer in either position and means for securing the same to a shirt sleeve. 10
2. As an article of manufacture, a detachable cuff for shirt sleeves comprising a cuff portion foldable to present different surfaces outwardly, in combination with a connecting band joining those ends of the cuff which extend parallel to the length of the wearer's arm and adapted to be turned inside out to present different surfaces toward the cuff, extending circumferentially of the wrist of the wearer in either position and a fastener adapted to be turned toward and engage the shirt sleeve in either of the reversed positions of the cuff. 20
3. As an article of manufacture, a detachable cuff for shirt sleeves comprising an outer part adapted to be reversed by folding in the direction of the length of the wearer's arm, a cuff band connected with those ends of said outer part which extend parallel to the length of the wearer's arm, and adapted to be turned inside out, extending circumferentially of the wrist of the wearer in either position and a tab carried by one of said parts adapted to be passed through a hole in the other part and 30 through the wrist band of a shirt for securing the cuff to the wrist band. 35
4. As an article of manufacture, a detachable cuff for shirt sleeves comprising an outer reversible part and a band connected with those edges of the reversible part which extend parallel to the length of the wearer's arm and turned wrong side out with reversal of the outer part, extending circumferentially of the wrist of the wearer in either position in combination with a retainer for engaging the shirt sleeve. 45
5. As a new article of manufacture, a detachable cuff for shirt sleeves, comprising an outer part adapted to be folded longitudinally, a cuff band of less width than 50 the outer part, the ends of which are secured to the inner sides of the cuff, said band and cuff being adapted to be reversed, the inside of the band then presenting a different face to the cuff, so as to cover a soiled and expose an unsoiled portion of said cuff, and means carried by said cuff for securing said cuff and cuff band to the central part of the wristband of the sleeve. 60
6. As a new article of manufacture, a detachable cuff for shirt sleeves, comprising an outer part adapted to be folded longitudinally, a cuff band of less width than the outer part the ends of said band being sewed to inner ends of said outer part, said outer part and said cuff band being adapted to be reversed, or turned inside out, and a tab carried by said outer part, adapted to be passed through holes or slits in said outer part, cuff band and the wristband of a shirt for 65 securing said cuff to said wristband. 70
7. As a new article of manufacture, a detachable cuff for shirt sleeves, comprising an outer part adapted to be folded longitudinally, a cuff band of less width than said outer part secured at its ends to the inner ends of said outer part, said outer part and cuff band being adapted to be reversed or turned inside out, and being furnished at opposite ends with button holes to receive a fastening, and a tab carried midway between the ends of said outer part of said cuff adapted to secure said cuff to the central part of a 75 wristband. 80
8. As a new article of manufacture, a detachable cuff for shirt sleeves comprising an outer part adapted to be folded longitudinally and an inner part of less length than the outer part, a cuff band of less width than the outer part the ends of which are sewed to the ends of the inner part, said band and cuff being adapted to be reversed, or turned inside out, so as to cover a soiled and expose an unsoiled portion of said cuff, a slot in said inner part, a tab sewed to said inner part 85 and adapted to be passed through said slot, said outer and inner parts of said cuff and said cuff band being furnished with holes for the passage of a cuff fastening or link and said cuff band being furnished with a 90 slot for the passage of said tab. 95
